UNITED STATES PATENT OFFICE.

CHARLES P. BYRD, OF ATLANTA, GEORGIA.

INKING MECHANISM.

SPECIFICATION forming part of Letters Patent No. 775,698, dated November 22, 1904.

Application filed March 30, 1904. Serial No. 200,779. (No model.)

To all whom it may concern:

Be it known that I, CHARLES P. BYRD, a citizen of the United States, residing at Atlanta, in the county of Fulton, State of Georgia, have 5 invented certain new and useful Improvements in Inking Mechanism; and I do hereby declare the following to be a full, clear, and exact description of the invention, such as will enable others skilled in the art to which it appertains 10 to make and use the same.

This invention relates to printing-presses, and more particularly to the ink-feeding mechanism thereof, and has for its object to provide a mechanism of this kind which will distribute the ink to the rollers when the press is in operation and which when the cylinder is tripped may be thrown out of gear to stop the feed of ink, and thus prevent double inking of the rollers. 15

In the drawings forming a portion of this 20 specification, and in which like numerals of reference indicate similar parts in the several views, Figure 1 is a top plan view of a portion of a press having the present invention applied thereto. Fig. 2 is a side elevation of Fig. 1. Fig. 3 is a section on line A B of Fig. 1. Fig. 4 is a detail side elevation of the ink-feeding mechanism. Fig. 5 is an end view of Fig. 4.

Referring now to the drawings, there is 25 shown a press 7, having an ink-reservoir 8 at one end, which contains the ink-feeding roller 9. This inking-roller, as shown, projects beyond the end of the reservoir 8 in the form of an axle or trunnion 10, and this trunnion has 30 secured thereto a ratchet-wheel 11. The trunnion 10 extends beyond the ratchet-wheel and has loosely mounted thereon a disk 12, which has a cut-away portion 13 in its periphery and a notch 14 at a point diametrically opposite to 35 the cut-away portion, as shown. One side of the notch 14 extends inwardly at right angles to the periphery of the disk 12, while the other side slants gradually from the periphery to the end of the straight side. The disk 12 is larger 40 than the wheel 11, so that the teeth of the wheel are exposed through the slot 14 and cut-away portion 13.

To the outer end of the trunnion 10 there is 45 attached a lever 15, which extends above and below the disk 12, and pivoted to the lever 15 is a pawl 16, which lies with its free end in

the notch 14 and which is held in engagement with the teeth of the wheel 11 by a spring 17. The lower end of the lever 15 is connected by 55 means of a pitman 18 to an eccentric 19 on the press, and when this eccentric is revolved the lever is caused to oscillate, and the pawl 16 successively engages the teeth of the wheel 11 to 60 revolve the roller 9 and feed the ink from the reservoir.

To the end of the press there is pivoted a hand-lever 20, carrying a roller 21, on which there rests a bar 22, having pivoted thereto a stop 23. A lever 24 is pivoted to the end of the lever 22, and this lever is connected by 65 means of a link 25 to the end of the stop 23, so that a toggle action is formed. A foot-plunger 26 is connected with an angular lever 27, pivoted to the frame of the press, and this lever is connected by means of a link 28 to the 70 end of the lever 24. The stop 23 has an arc-shaped portion 29, which has projecting from the ends thereof two points 30 and 31, which are disposed for engagement with the cut-away portion of the disk 12. The projection 31 lies 75 normally in engagement with one end of the cut-away portion 13 to prevent rotation of the disk 12 and hold the notch 14 in position to permit the pawl 16 to engage the teeth of the wheel 11. In the face of the disk 12 there are 80 a pair of spaced recesses 32 and 32', and projecting from the lever 15 is a spring-pressed lug 33. The lug 33 lies normally in engagement with the recess 32', so that the disk 12 is 85 oscillated with the lever 15.

As described above, when the press is in operation the ink is fed from the reservoir by the roller 9, and in presses which utilize this system of inking considerable difficulty has 90 been experienced in preventing double inking of the distributing-rollers and the type when the press is tripped—*i. e.*, when the cylinder is raised from the type and no impression is taken—the result being that when the next impression is made a superabundance of 95 ink is deposited on the paper and the print is ruined. As stated above, the object of this invention is to prevent this double inking, which is accomplished in the following manner:

When the press is tripped, the foot-plunger 24 is depressed, which operates the toggle action described above, causing the pro-

jection 31 to become disengaged from the cut-away portion of the disk while engaging the projection 30 therewith. The engagement of the projection 30 with the end of the cut-away portion prevents the disk 12 from moving with the lever 15, so that the lug 33 leaves the recess 32' and enters the recess 32, so that the pawl 16 is held out of engagement with the teeth of the wheel 11 by the slanting face of the notch 14. While the parts are in this position, movement of the disk 12 is limited by the projection 30, and the roller 9 remains stationary until the plunger 26 is released, and the projection 31 is again engaged with the cut-away portion 13. When this occurs, the limit of movement of the disk 12 is changed and the lug 33 is moved from the recess 32 back again to the recess 32', the pawl 16 coming again into engagement with the teeth of the wheel 11 to operate the roller 9. The foot-plunger 26 is also connected with the tripping mechanism of the press, so that the single operation of depressing the plunger both trips the press and cuts off the supply of ink.

When it is desired to throw the above mechanism out of operative position in order to supply a large quantity of ink to the rollers through repeated inking while the press is tripped, the hand-lever 20 is lowered, which moves the bar 22 downwardly and disengages the stop 23 from the disk 12, after which the fountain is free to operate when the press is tripped.

Loosely disposed upon the shaft 10 is an ink-regulating disk 34, which has projecting from its outer face an arc-shaped lug 35, having a beveled end 36, and this disk is rotatable upon the shaft to bring the end 36 of the lug into the path of movement of the pawl 16, so that as this pawl is moved rearwardly it rides up over the lug and is moved out of contact with the teeth of the wheel 11. The disk 34 may thus be adjusted to permit the pawl 16 to engage only the desired number of teeth, and thus the rotation of the roller 9 may be regulated to feed the desired quantity of ink to the inking-rollers. The disk 34 is provided with notches 37 in its periphery, with which may be engaged a dog 38 to hold the disk in the desired position.

In practice modifications of the specific construction shown may be made, and any suitable materials and proportions may be used for the various parts without departing from the spirit of the invention.

What is claimed is—

1. An ink-feeding mechanism for printing-presses comprising a reservoir, a feed-roller 60 mounted in the reservoir and having a trunnion extending outwardly thereof, a ratchet-disk mounted upon the trunnion, a lever pivoted upon the trunnion, means for oscillating the lever, a pawl pivoted to the lever and lying normally in engagement with the teeth

of the ratchet-disk to rotate the latter when the lever is moved in one direction, a cam-disk loosely mounted upon the trunnion between the lever and ratchet-disk, and arranged for engagement of its cam-face with the pawl 70 to move the latter out of its normal position, said disk lying normally out of such position and having spaced recesses therein, a pin carried by the lever and lying normally in engagement with one of the recesses to hold the 75 cam-disk in its normal position, and means for moving the lever with respect to the disk to engage its pin with the remaining recess to bring the cam-disk into engagement with the pawl to hold the latter out of engagement 80 with the teeth of the ratchet-disk.

2. An ink-feeding mechanism for printing-presses comprising a reservoir, a feed-roller revolvably mounted in the reservoir, a ratchet-disk carried by the roller for rotation therewith, a pivotally-mounted lever, means for oscillating the lever, a pawl pivoted to the lever and lying normally in engagement with the teeth of the ratchet-disk to rotate the latter when the lever is moved in one direction, 85 a cam-disk arranged for movement to bring its cam-face into engagement with the pawl to hold the pawl out of its normal position, said disk lying normally out of such position, said disk having spaced recesses therein, a pin carried by the lever and arranged for interchangeable engagement with the recesses, said disk lying in its normal position when the pin is in engagement with one of its recesses, and lying when the pin is engaged 90 with its other recess with its cam-face in engagement with the pawl, and means for holding the disk against movement to permit of movement of the lever to bring its pin into interchangeable engagement with the recesses. 100

3. An ink-feeding mechanism for printing-presses comprising a reservoir, a feed-roller mounted in the reservoir, a ratchet-disk carried by the roller, a pivotally-mounted lever, means for oscillating the lever, a pawl carried 110 by the lever and lying normally in engagement with the teeth of the ratchet-disk to rotate the latter when the lever is moved in one direction, a cam-disk arranged for movement to bring its cam-face into engagement with the pawl to hold the latter out of engagement 115 with the ratchet-disk, said cam-disk lying normally out of such position, means for oscillating the cam-disk with the lever when the disk is in its normal position, means for shifting the cam-disk with respect to the lever to bring its cam-face in engagement with the pawl, and means for oscillating the cam-disk when in its last-named position. 120

In testimony whereof I affix my signature in presence of two witnesses.
